Primary Examiner — Mary Ann Calabrese(74) *Attorney, Agent, or Firm* — Skinner and Associates(57) **CLAIM**

The ornamental design for a combined tag and carabiner, as shown and described.

DESCRIPTION

FIG. 1 is a perspective view of a combined tag and carabiner showing the new design of this invention.

FIG. 2 is a perspective view of the combined tag and carabiner.

FIG. 3 is a front view of the combined tag and carabiner.

FIG. 4 is a back view of the combined tag and carabiner.

FIG. 5 is a side view of the combined tag and carabiner, the opposite side being symmetrical.

FIG. 6 is a top view of the combined tag and carabiner; and, FIG. 7 is a bottom view of the combined tag and carabiner. The broken lines shown in FIG. 1 are for illustrative purposes only and form no part of the claimed design.
